(12) **United States Design Patent** (10) **Patent No.:** **US D1,017,040 S**
(45) **Date of Patent:** **** Mar. 5, 2024**

(54) **HANDHELD ENDOSCOPIC IMAGING DEVICE**

(71) Applicant: **SBI ALAPHARMA CANADA, INC.**,
Toronto (CA)

(72) Inventors: **Ralph S. Dacosta**, Toronto (CA);
Kathryn Ottolino-Perry, Toronto (CA); **Christopher Gibson**, Toronto (CA); **Nayana Thalanki Anantha**, Toronto (CA); **Simon Treadwell**, Toronto (CA); **Todd Daynes**, Aurora (CA); **Todd Meaney**, Thornhill (CA)

(73) Assignees: **SBI ALAPHARMA CANADA, INC.**,
Toronto (CA); **University Health Network**, Toronto (CA)

(**) Term: **15 Years**

(21) Appl. No.: **29/842,182**

(22) Filed: **Jun. 10, 2022**

CLAIM

The ornamental design for a handheld endoscopic imaging device, as shown and described.

DESCRIPTION

FIG. 1 is a back, left side perspective view of an embodiment of a Handheld endoscopic imaging device showing our new design.

FIG. 2 is a bottom view thereof.

FIG. 3 is a top view thereof.

FIG. 4 is a right side view thereof.

FIG. 5 is a left side view thereof.

FIG. 6 is a back view thereof; and,

FIG. 7 is a front view thereof.

The broken lines show portions of the handheld endoscopic imaging device that form no part of the claimed design.
